UNITED STATES PATENT OFFICE.

WILLIAM W. WEITLING, OF COLLEGE POINT, AND AUGUSTUS M. HENRY, OF BROOKLYN, NEW YORK, ASSIGNORS TO WILLIAM W. WEITLING, OF COLLEGE POINT, LONG ISLAND, NEW YORK, TRUSTEE FOR HIMSELF; AUGUSTUS M. HENRY, AND ROBERTO M. PEAKE.

ROTARY CASTING.

Application filed September 5, 1924. Serial No. 736,098.

This invention relates to the art of casting metals, especially ferrous metals as iron and even steel, by the rotary or so-called centrifugal method.

- 5 Consequently the invention is of special importance, viewing the scope of protection contemplated most broadly, in the art of making articles of annular cross section by the rotary casting method.
- 10 The cardinal object of the present invention is to provide methods of and means for attaining, in connection with an operatively combined mold and boiler structure, the various objects and advantages of the joint 15 invention of Charles Horton and the above-named Augustus M. Henry as disclosed in their joint application Serial No. 727,417, filed July 22, 1924; for attaining the further objects and advantages of the invention 20 of said Horton's application Serial No. 727,418, filed July 22, 1924 (said Horton application providing a way of avoiding the necessity of rotating the low pressure boiler as well as the high pressure boiler and 25 mold); and for attaining also the objects and advantages of the invention of said Horton's application Serial No. 732,470, filed August 16, 1924 (said Horton application last mentioned providing, for one thing, 30 a way of avoiding the necessity even of rotating the high pressure boiler with the mold, and, for another, a way of reducing the pressure-with-standing requirements of said "high pressure" boiler).
- 35 Otherwise expressed, briefly, the present invention has two main objects:

First, to provide an improved substitute, to wit, linseed oil, for the "liquid" for the "high pressure" boiler stated in said Horton application Serial No. 732,470 to be preferred, to wit, mercury—since it has just been ascertained that the boiling or vaporization point of linseed oil, costing immensely less than mercury (a few cents per pound as 45 against eighty cents), is substantially as high as that of mercury; and

Second, to provide an improved substitute for what may be termed the "slip-sleeve" forming a permanently inbuilt part of the 50 self-complete mold "cartridge" disclosed in said Horton sole application Serial No. 732,470—such substitute being either a mass of pulverized graphite, or a solid sleeve

thereof, used in lieu of the steel wool, or steel wool and graphite, conglomeration proposed 55 by Horton in said application Serial No. 732,470.

Although linseed oil appears at present to be the perfect material for the boiling liquid, it is believed that other non-aqueous 60 substances may be employed, such as other oils.

The invention itself, and other objects sought and advantages attained than those hereinabove specifically mentioned, will be 65 most clearly understood from the following description of an exemplifying apparatus as at present preferred, and as illustrated in the accompanying drawings, in which

Fig. 1 is a transverse vertical section 70 taken through the apparatus; and

Figs. 2 and 3 show respectively the opposite ends of the apparatus, these views being partially in vertical longitudinal section and partially in side elevation. 75

Similar reference characters refer to similar parts throughout the several views of the drawings.

Referring now more particularly to such drawings, at 1 is represented the mold cavity, at 2 the mold, at 3 the inside shell of the annular boiler containing the linseed oil 4, at 5 the outside shell of said boiler, at 6 the condensing dome containing the oil vapor and at 7 the heat-absorbing steam boiler. This dome is exteriorly threaded at its cylindrical lower portion as shown in Figs. 1 and 2, which threads take matching internal threads in a steel collar-casting 6a. This casting, which is riveted as shown to 80 shell 5, is welded to shell 5 at dome 6 as indicated to seal the oil chamber and dome hermetically when the powerful needle valve 8 (of the type commonly used on containers for liquefied gases) is closed. 85

Through this valve the quantity of oil contained in the annular chamber 4 may be changed and also gases under pressure may be introduced for varying the boiling point of the oil. 90

The mold 2 is supported in bearings 9 and 10 of the water-cooled Hyatt-roller type by means of the conical or taper surfaces 11 and 12. 100

The mold is arranged to be rotated in 105 these bearings by means not shown and in

2
 contact with a heat conducting packing 13 which at present is preferably a mass of powdered graphite or a solid sleeve of graphite or a cylinder made up of graphite 5 bricks, or of some such graphite construction. Such packing persists as a filler-mass between mold and sleeve 14, permits the rapid transfer of heat from the mold to the shell 2 of the oil container, and yet acts as 10 an anti-friction slip-sleeve to permit easy rotation of the mold, in spite of close packing of the graphite.

The use of the machine shown contemplates moulds of different internal diameters 15 for various size castings, and consequently the mold and the graphite mass are kept together and arranged for easy removal from the bearings by providing the just-mentioned retaining shell 14 which contacts the 20 shell 3 and remains stationary with the graphite in use; that is, these elements 2, 13 and 14 constitute the unitary cartridge already mentioned. As shown, the retaining shell 14 is held against longitudinal movement 25 relatively of the cartridge, but is rotatable relative to the remaining parts of the cartridge. When it is desired to renew the mold, or substitute a mold of a different pipe-size, the cartridge is pulled out and another cartridge inserted. Obviously, the 30 machine is so designed, or may well be so designed, as to take care of a great range of cartridges of different diameters, that is, cartridges having molds of different internal 35 diameters; each such cartridge, however, having a shell 14 of the same external diameter, the other dimensional problems being taken care of by varying the thicknesses of the mold, the shell 14 and the annular 40 filler 13 or the thicknesses of two thereof or the thickness of the filler.

It is desirable, indeed essential, for most economical operation, that the liquid containing chambers be heat insulated as indicated at 15.

We claim:

1. In the art of rotary casting, the method of controlling the rate of heat-conduction from the molten-metal pour through the 50 mold, which involves rotating the mold while maintaining the mold in heat-transfer relation to a collection of linseed oil, and confining such collection of oil adjacent to the mold to vaporize a portion of said liquid.

2. In the art of rotary casting, the method of controlling the rate of heat-conduction

from the molten-metal pour through the mold, which involves rotating the mold while maintaining the mold in heat-transfer relation to a collection of oil, and confining 60 such collection of oil adjacent to the mold to vaporize a portion of said oil, and while also confining the vaporized portion of such oil, confining a liquid vaporizable at a lower temperature than said oil, and maintaining 65 the two liquids in heat-transfer relation.

3. In the art of rotary casting, the method of controlling the rate of heat-conduction from the molten-metal pour through the mold, which involves rotating the mold 70 while maintaining the mold in heat-transfer relation to a collection of oil and confining such collection of oil adjacent to the mold to vaporize a portion of said oil, and condensing such vaporized portion of the oil 75 and returning the same to said collection.

4. In the art of rotary casting, the method of controlling the rate of heat-conduction from the molten-metal pour through the mold, which involves providing a mold, confining an oil in heat transfer relation to the mold, and rotating the mold relative to said oil during forming and cooling of a molten-metal charge in the mold, said oil having a vaporization temperature substantially as 80 high as liquid mercury.

5. In the art of rotary casting, the method of controlling the rate of heat-conduction from the molten-metal pour through the mold, which involves providing a mold, confining non-metallic liquid in heat transfer 90 relation to the mold, and rotating the mold relative to said liquid during forming and cooling of a molten-metal charge in the mold, said liquid having a vaporization temperature substantially as high as liquid mercury but not substantially higher than the 95 temperature whereat the molten metal charge (if ferrous metal) attains its third shrinkage during cooling.

6. In a rotary casting machine, a rotary mold, an oil boiler in heat-transfer relation to the same, a vaporization chamber for the oil carried by the boiler, and a steam boiler in heat-transfer relation to said chamber. 100

7. In a rotary casting machine, a rotary mold, an oil boiler in heat-transfer relation to the same, and steam boiler in heat-transfer relation to the oil-boiler. 105
